UNITED STATES PATENT OFFICE.

JOHN B. SHAFFER, OF KEARNEY, NEBRASKA.

STEAM-ENGINE.

SPECIFICATION forming part of Letters Patent No. 273,171, dated February 27, 1883.

Application filed May 2, 1882. (No model.)

To all whom it may concern:

Be it known that I, JOHN B. SHAFFER, of Kearney, in the county of Buffalo and State of Nebraska, have invented new and useful 5 Improvements in Steam-Engines, of which the following is a full, clear, and exact description.

Reference is to be had to the accompanying drawings, forming part of this specification, in which similar letters of reference indicate corresponding parts in all the figures.

Figure 1 represents a side elevation of a compound engine constructed in accordance with my invention. Fig. 2 is a plan view of the same. Fig. 3 is a side view of the two cranks 15 of the engine; and Fig. 4, a vertical transverse section upon a larger scale, showing a peculiarly-constructed piston-rod guide.

The invention relates to improvements in steam-engines; and it consists in the peculiar 20 construction and arrangement of parts, as hereinafter fully described, and pointed out in the claim.

In the drawings, A indicates the high-pressure cylinder of the engine, and B the low-pressure 25 cylinder thereof. These cylinders are arranged one below the other, but not parallel with each other, their axial lines, if extended, meeting in an acute angle at the center of the engine-shaft C. The low-pressure cylinder B is of double the length of stroke, or thereabout, of the high-pressure cylinder A. The cylinders A, B are provided with piston-rods 30 b c, having pistons of the usual construction, for reciprocating in the cylinders. The rod b of the high-pressure-cylinder piston is connected to a sliding cross-head, d, to which is 35 connected a pitman, e, that connects with a wrist-pin, f, on a disk, F, which is fast on the engine-shaft C, while the rod c of the low-pressure-cylinder piston is connected to a cross-head, g, from which is a pitman, h, that connects with the 40 wrist-pin i of a second crank or arm, G, which is fast on the wrist-pin f. In such arrangement the disk F forms the one crank and the arm G the other of a compound or double 45 crank, as shown in Fig. 3, in which a crank proper is substituted for the disk. These cranks are so set that when either one is on its dead-center the other one is on the quarter-circle. 50 Consequently the engine is free from dead-center action or pressure, and a fly-wheel for pass-

ing the cranks over their dead-centers may be dispensed with. The low-pressure cylinder B has its slide-valve operated by an eccentric, k, and rod l from the engine-shaft C.

The motion of the engine may be reversed by slackening a set-screw, r, which locks a key, s, that secures the crank G on the wrist-pin f, taking out said key and moving the parts around till the keyway in said crank comes in line with a second keyway, u, in the wrist-pin, when the key may be inserted and the set-screw tightened to hold the crank G in the changed position on the wrist-pin, the eccentric which operates the valve also being changed to correspond.

J is a circular main frame, having an opening in its center for insertion of the main bearing, which carries the engine-shaft. This frame, which acts as a brace, is extended to also form 70 ways l' l', on which anti-friction rollers m' m', arranged at the ends of the cross-head g, travel. These anti-friction rollers are grooved to fit said ways, and are carried by boxes or frames m², adjustable within either end of the cross-head relatively to either way by means of a key, n', to secure a close but easy fit of said rollers on or against the ways, and whereby friction of the cross-head is materially reduced. Said frame J is suitably constructed to provide 75 80 for the working of the pitman e through and within it.

The cross-head d of the piston-rod of the high-pressure cylinder is constructed to slide on and along guides o² o², which project from 85 and may be in one piece with the head or cover of the cylinder A.

The brace-frame J and the parts connected therewith form no part of the present application, and I desire it to be understood that I 90 reserve the right hereafter to make a separate application for Letters Patent therefor.

When the engine is a stationary one a governor, K, is applied. This governor may consist of an upright frame, rotated by gearing 95 which derives its motion from the engine-shaft, said frame rotating upon and around a fixed standard, and carrying three (more or less) bowed steel wires or springs, a³, which are attached at their upper ends to a head-piece 100 mounted on a rod that is capable of moving up and down within a central tubular upright

of the frame for the purpose of controlling a valve on the bottom of said rod within the steam-inlet. Upon the steel wires a^3 are any number of adjustable balls or weights, which, by their centrifugal motion, in common with the wires a^3 , more or less flex said wires, according to the speed at which the governor runs, and so raise or lower the valve-rod, with its attached valve. This governor, together with means for preventing backlash of the gearing by which it is driven, and for steady-ing the motion of the governor, it is my intention to make the subject of a separate application for Letters Patent.

I am aware that cylinders arranged at angles to each other and driven by a double crank from a single drive-shaft are not broadly new; and I therefore do not claim such, my inven-

tion being confined to the particular construction and arrangement of parts as pointed out in the claim.

Having thus fully described my invention, what I claim as new, and desire to secure by Letters Patent, is—

The combination, with cylinders A B, arranged at an angle to each other, the double crank F G, and the ways $l^1 l^2 o^2 o^2$, of the pit-men $h e$, the cross-heads $d g$, the anti-friction rollers m' , the adjustable bearings m^2 , and the adjusting-wedges n' , substantially as and for the purpose set forth.

JOHN B. SHAFFER.
